UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

DOOR BUFFER.

Application filed November 17, 1924. Serial No. 750,426.

To all whom it may concern:

Be it known that I, WILLIAM MARSHALL, a citizen of the United States of America, residing at Detroit, in the county of Wayne 5 and State of Michigan, have invented certain new and useful Improvements in Door Buffers, of which the following is a specification, reference being had therein to the accompanying drawing.

This invention relates generally to buffers and refers more particularly to those designed for cushioning doors and the like.

One of the essential objects of the invention is to provide a simple and inexpensive 15 buffer of this type that may be easily and quickly attached to a metallic door jamb.

Another object is to provide a buffer having abutment faces that extend transversely of each other so that the door may be cushioned in several directions.

A further object is to provide a buffer that is preferably formed of resilient material and is of uniform cross section throughout its length so that it may be cut from a 25 long strip of the desired shape.

With the above and other objects in view the invention consists in certain novel features of construction, combinations and arrangements of parts as will be more fully 30 described and particularly pointed out in the appended claims.

In the accompanying drawing;

Figure 1 is a perspective view of a door 35 jamb with a buffer embodying my invention applied thereto.

Figure 2 is a horizontal sectional view taken on the line 2—2 of Figure 1.

Figure 3 is a rear elevation of the buffer.

Referring now to the drawing in which 40 like characters of reference designate corresponding parts throughout the several views, the numeral 1 designates a door jamb, preferably of a vehicle body of the closed type. This jamb may be any shape desired, 45 but is preferably formed of sheet metal and is provided at its inner edge with a laterally extending flange 2.

The buffer 3 may be formed of any suitable yieldable material such as rubber, but 50 is preferably L-shape in cross section so that the inner side and rear faces 4 and 5 respectively thereof will fit snugly against the jamb and lateral flange thereof when the parts are assembled. As shown in Figure 55 2, the lateral portion 6 is considerably

thicker than the main portion 7 and is provided at its rear face with a longitudinally extending rib 8 that is engageable with a longitudinally extending substantially rectangular shaped opening 9 in the lateral 60 flange 2, while the main portion 7 of the buffer is preferably provided at its outer edge with a laterally extending rib 10 that extends longitudinally thereof and is engageable with a vertically extending substantially rectangular shaped opening 11 in the side of the door jamb.

The buffer is positioned upon the door jamb by first inserting the rib 8 into the opening 9 in the lateral flange 2 and then 70 forcing the buffer inwardly so that the rib 10 will project through the opening 11 in the side of the door jamb. The inner and rear faces 4 and 5 respectively of the buffer will then be seated snugly against the side 75 and flange of the door jamb. Due to the angular formation, the ribs 8 and 10 respectively of the buffer will not become accidentally disengaged from the openings 9 and 11, hence the buffer will be anchored 80 firmly in place.

From the foregoing description it will be readily apparent that the lateral portion 6 of the buffer will effectively absorb the 85 shocks incident to closing the door. When the door is closed, the main portion 7 will absorb any vibrations caused by the door being urged toward the jamb and the lateral portion 6 will then absorb any vibrations caused by the door being urged inwardly 90 beyond the lateral flange 2 resulting in any weaving or twisting action to which the vehicle body may be subjected while in motion. Hence the angular formation of my 95 buffer is a very important feature that possesses many advantages over other rubber buffers now in use.

Inasmuch as the buffer is of uniform cross section throughout its length, it will also be 100 readily apparent that individual buffers can be readily made by cutting a long strip of resilient material of the proper shape into the desired lengths. Thus the manufacture of such buffers is simplified considerably.

While it is believed that from the foregoing description the nature and advantages of the invention will be readily apparent, I 105 desire to have it understood that I do not limit myself to what is herein shown and described, and that such changes may be re-

sorted to when desired as fall within the scope of what is claimed.

What I claim as my invention is:

1. The combination with a metal door jamb having a lateral flange, of a door buffer having a portion seating against the outer face of the jamb, and having a portion seating against the outer face of the flange, and projections extending from the portion 10 aforesaid of said buffer extending through said jamb and flange respectively.

2. A door buffer having portions extending transversely of each other, each portion having a longitudinally extending rib projecting therefrom, the rib on one portion being disposed in a plane at substantially right angles to the rib on the other portion.

3. A door buffer comprising a resilient body of substantially L-shape in cross section having a laterally extending rib and a

rearwardly extending rib projecting therefrom.

4. The combination with a door jamb having a wall provided with a lateral flange, of a door buffer carried by the jamb including a resilient block having diverging portions, one portion of said block being secured to the wall aforesaid of said jamb, and the other portion of said block being secured to said flange.

5. The combination with a door jamb having diverging walls, of a resilient buffer having diverging portions seated against the diverging walls aforesaid, each of said portions having a lateral projection extending transversely of the adjacent wall of said pillar.

In testimony whereof I affix my signature.

WILLIAM MARSHALL.
